INVENTOR

J. A. STORM.
BY *Adam E. Cooper*
ATTORNEY

UNITED STATES PATENT OFFICE.

JAMES A. STORM, OF ST. LOUIS, MISSOURI.

HAT HOLDER.

1,419,325.

Specification of Letters Patent. Patented June 13, 1922.

Application filed March 6, 1919. Serial No. 281,087.

To all whom it may concern:

Be it known that I, JAMES A. STORM, a citizen of the United States, residing in the city of St. Louis and State of Missouri, have 5 invented new and useful Improvements in Hat Holders, of which the following is a specification, reference being had to the accompanying drawings.

This invention pertains to devices for conveniently holding and retaining the hat upon the head of the wearer. The ordinary difficulty of maintaining a hat in conventional position on the head of the wearer, especially in windy weather or while riding 15 in vehicles, is well known and is a source of great annoyance and inconvenience.

The primary object of this invention, therefore, is to provide a head hat hold, constructed in a simple, inexpensive, attractive 20 and convenient form, and which may be readily and quickly attached to or detached from the sweat-band of the hat, and which when in proper position and adjustment will effectually hold the hat upon the head of the 25 wearer.

With this object in view, attention is called to the accompanying drawings constituting a part of this specification, wherein:

30 Figure 1 is a perspective view of my device as attached to the sweat-band of a hat and adapted for holding the hat upon the head, taking its hold directly from the back portion of the head;

35 Figure 2 is a similar perspective showing the attachment as taking its hold directly from underneath the chin of the wearer;

Figure 3 is a similar perspective showing the attachment with the band extended over 40 the ears of the wearer and thence under the chin;

Figure 4 is a detail showing one of the preferred methods of attaching the device to the sweat-band of the hat;

45 Figures 5, 6, 7, 8 and 9 show modified methods of attaching the device to the said sweat-band, or sides of the hat.

Fig. 10 is a perspective view of an adjustable clamp for joining the lower ends of the 50 sections of the hat holder.

Referring more particularly to the drawings, my invention in its preferred construction, consists in combination with the ordi-

nary sweat-band 1 of the hat 2, of a retaining band A made preferably in two half 55 sections as 3 and 4, fastened together at the lower ends by means of any suitable fastening such as the adjustable buckle 5. The upper ends of the sections 3 and 4 are provided with elongated hooks such as 6 and 7, 60 same being turned preferably outwardly. The hooks 6 and 7 are adapted to engage the hat band 1 by means of two apertures 8 and 9 piercing said hat band at opposite sides thereof. The apertures 8 and 9 may be reinforced by eyelets such as 10 and 11, if desired, although such eyelets are not indispensable. This construction affords a detachable and pivotal connection which is self adjusting to the different positions of 70 the band A. By constructing the retaining band A in two parts, as 3 and 4, and adjustably connecting these parts with the fastening 5, a means of adjusting the band to any required length is afforded, so as to efficiently adapt the device to the head of the 75 wearer. Thus the band A may be lengthened or shortened as desired.

A modified method of attaching the retaining band A to the sweat-band 1 is shown 80 in Figure 5 wherein, instead of the sweat-band being pierced with the apertures 8 and 9, detachable clamps such as 12 and 13 are provided, same being fastened upon the said sweat-band 1 from the upper edge thereof 85 and being held in place thereon by frictional engagement. To these clamps in turn, the ends of the retaining band A are attached. Or the band A may be hingedly attached to the clamps 12 and 13 by means of a hinged 90 connection 14, as shown in Figure 6, and when not in use the band A may be drawn up inside the hat, as shown in Figure 7. Or the apertures 8 and 9, and the hooks 6 and 7, may extend clear through the sides of the 95 hat, as shown in Figure 8. Or as shown in Figure 9, rings or tabs such as 15 may be joined directly to the sides of the hat, for attaching the retaining band A in lieu of the other methods of attachment shown. This 100 method is especially suited to ladies' hats, where no sweat-band is used.

While I have herein described certain specific methods of constructing and assembling the elements of my invention, it is understood same may be varied in minor de-

tails, not departing from the spirit of my invention as defined in the appended claim.

What I claim to be new and patentable is:

In combination with the inner sweat band 5 of a hat, said band being pierced with oppositely located eyelets; a hat holder comprising a retaining band including two pieces

adjustably connected to each other; and hooks at the free ends for releasably engaging said eyelets.

JAMES A. STORM.
